CLAIM

The ornamental design for a hair trimmer as shown and described.

DESCRIPTION

FIG. 1 is a top perspective view of a hair trimmer;
 FIG. 2 is a left side view thereof;
 FIG. 3 is a right side view thereof;
 FIG. 4 is a front view thereof;
 FIG. 5 is a rear view thereof;
 FIG. 6 is a top view thereof; and,
 FIG. 7 is a bottom view thereof.
 In the drawings the broken lines illustrate portions of the hair trimmer and form no part of the claimed design.
